[57] CLAIM

The ornamental design for a hedge trimmer, as shown and described.

DESCRIPTION

FIG. 1 is a right side elevational view of a hedge trimmer embodying our design;
FIG. 2 is a left side elevational view thereof;
FIG. 3 is a top plan view thereof;
FIG. 4 is a bottom plan view thereof;
FIG. 5 is a rear elevational view thereof;
FIG. 6 is a front elevational view thereof;
FIG. 7 is a right side perspective view thereof;
FIG. 8 is a left side perspective view thereof;
FIG. 9 is an enlarged right side elevational view of an engine and handle portion thereof;
FIG. 10 is an enlarged right side elevational view of a blade portion thereof;
FIG. 11 is an enlarged left side elevational view of an engine and handle portion thereof;
FIG. 12 is an enlarged left side elevational view of blade portion thereof;
FIG. 13 is an enlarged top plan view of an engine and handle portion thereof;
FIG. 14 is an enlarged top plan view of a blade portion thereof;
FIG. 15 is an enlarged bottom plan view of an engine and handle portion thereof;
FIG. 16 is an enlarged bottom plan view of a blade portion thereof;
FIG. 17 is an enlarged rear elevational view thereof; and,
FIG. 18 is an enlarged front elevational view thereof.
